UNITED STATES PATENT OFFICE.

HANS SIBER, OF SÖMMERDA, GERMANY.

MEANS FOR UNITING GUN-BARRELS.

SPECIFICATION forming part of Letters Patent No. 661,745, dated November 13, 1900.

Application filed May 16, 1900. Serial No. 16,838. (No model.)

To all whom it may concern:

Be it known that I, HANS SIBER, manager, captain, emtd., a subject of the King of Prussia, German Emperor, residing at Sömmersda, 5 Kingdom of Prussia, German Empire, have invented certain new and useful Improvements in Means for Connecting the Barrels of Double-Barreled Sporting-Guns and the Like with the Breech-Piece; and I do hereby 10 declare the following to be a full, clear, and exact description of the invention, such as will enable others skilled in the art to which it appertains to make and use the same.

This invention has for its object an improved 15 means for connecting the barrels of double-barreled sporting-guns and the like with the barrel-lug, and it is a question of forming such a connection that a mechanical coupling of the barrels with the barrel-lug or closing- 20 piece takes place by the assistance of soft soldering. Such barrel joints or connections are already frequently known, which, however, fulfil their object in only a more or less complete manner. The present barrel connection, 25 however, has an essentially greater solidity than these older arrangements, and the same affords an additional security against unintentional loosening of the barrels, even when the solder is temporarily removed from the 30 respective parts of the barrel by extraordinary heating. This security is effected by a separate insertion or locking bar, which is inserted after the connection of the barrels with the barrel-lug and which holds the latter from 35 both sides by means of dovetail-shaped projections engaging in suitable grooves, whereby the barrels are themselves immovably fixed on the barrel-lug. This improved method of arrangement is shown in the accompanying 40 drawings, in which—

Figure 1 is a side view of the barrel and barrel-lug; Fig. 2, a front view; Fig. 3, a plan view of the same. Fig. 4 shows the parts when separated. Figs. 5 and 6 are respectively a 45 plan view and side view of one of the barrels. Figs. 7 and 8 are respectively a view from beneath and a plan view of the fixing-bar.

Each of the two barrels *a* and *b* is provided with two sets of dovetail-shaped projections 50 and corresponding grooves standing at right angles to one another. In the form of construction shown the barrels have each two projections or lugs 3 and 4 underneath, while on the sides which face one another they have 55 grooves or channels 1 and 2. The grooves or

channels run transversely to the longitudinal direction of the barrels and are of course of such a profile that after the connection has been established all the parts are firmly connected with one another without any play. 60 Corresponding to the projections 3 and 4 of the barrels grooves *c*³ and *c*⁴ are provided in the barrel-lug *c*, which is flattened off horizontally to both sides in such a way that the barrels may be pushed thereon laterally when 65 making the connection.

In order to obtain the final connection, or rather to more particularly secure the connection, an insertion-piece or locking-bar *d*, provided on both sides with two dovetail-shaped projections *d*¹ *d*², is employed. The projections *d*¹ *d*² fit in the side grooves 1 and 2 of the barrels, so that when these latter have been mounted upon the barrel-lug the locking-bar can be inserted from above. In 75 its inserted position this then holds both barrels together, while at the same time securing their fixed position on the barrel-lug. The hook-shaped projections or hooks situated on the front and rear ends of the locking-bar 80 *d*, the arrangement and form of which projections are shown more particularly in Fig. 8, are intended for increasing the security of the permanent fixing and simultaneously for receiving and distributing the recoil in a 85 straight line over the whole system.

What I claim is—

1. The combination, with two laterally-slidable gun-barrels, and a barrel-lug connected to one side of each of them; of a vertically-slidable locking-bar which secures the said barrels together and prevents them from sliding laterally on the said barrel-lug, said lug, bar and barrels being provided with interlocking portions on their adjacent surfaces, 95 substantially as set forth.

2. The combination, with two gun-barrels, of a barrel-lug secured on one side of the said barrels, and a locking-bar secured between the said barrels and provided with projections 100 at its ends which engage with the central portion of the said barrel-lug, substantially as set forth.

In testimony whereof I affix my signature in presence of two witnesses.

HANS SIBER.
